[57] **CLAIM**

The ornamental design for a pump head, as shown and described.

DESCRIPTION

FIG. 1 is a front elevation view of the pump head of my design.

FIG. 2 is a rear elevation view thereof.

FIG. 3 is a right side elevation view thereof.

FIG. 4 is a left side elevation view thereof.

FIG. 5 is a top plan view thereof.

FIG. 6 is a bottom plan view thereof.

FIG. 7 is a front elevation view of a first alternate embodiment thereof.

FIG. 8 is a rear side elevation view thereof.

FIG. 9 is a right side elevation view thereof.

FIG. 10 is a left side elevation view thereof.

FIG. 11 is a top plan view thereof; and,

FIG. 12 is a bottom plan view thereof.

The broken line showing of a container is for illustrative purposes only and forms no part of the claimed design.
